VESSEL FILLING VALVE

Ranold F. Quam, Milwaukee, Wis.

Application January 14, 1949, Serial No. 70,920

12 Claims. (Cl. 226—124)

1

This invention relates to improvements in vessel filling valves.

In filling bottles or the like with liquids such as milk, the tendency of said liquids to foam seriously interferes with the filling operation when conventional filling valves are used. This foaming necessitates the slowing down of the filling operation to a rate at which a minimum amount of foam is produced and necessarily results in low efficiency.

My copending application Serial No. 41,995, filed August 2, 1948, discloses a vessel filling valve of the same general type as the present invention, but which operates by being lowered into sealing engagement with the upper end of the vessel to be filled, rather than by having the vessel raised into operative relationship therewith.

It is a general object of this invention to provide a valve adapted to be more rapidly operated to expedite the filling of vessels with a liquid, the filling operation, when said valve is used, being substantially unaffected by the formation of foam from said liquid.

A further object of the invention is to provide a valve of the class described which may be quickly and easily disassembled and cleaned, and which is well adapted for use in the food industry.

A further object of the invention is to provide a vessel filling valve of the class described which is adapted for use with a pedestal type vessel filling machine wherein the vessel to be filled is raised into operative position.

A further object of the invention is to provide a vessel filling valve which is strong and durable, which is fast and positive in its operation, and which is easy to manufacture and repair.

With the above and other objects in view, the invention consists of the improved vessel filling valve and all of its parts and combinations as set forth in the claims, and all equivalents thereof.

In the drawing accompanying and forming a part of this specification, wherein is shown one complete embodiment of the preferred form of the invention and wherein the same reference characters indicate the same parts in all of the views:

Fig. 1 is a side view of the improved valve in closed position;

Fig. 2 is a vertical sectional view of the improved valve taken along the line 2—2 of Fig. 1;

Fig. 3 is a view similar to Fig. 2 showing the improved valve in open position with a bottle in operative relation therewith;

2

Fig. 4 is a transverse sectional view taken along the line 4—4 of Fig. 1; and

Fig. 5 is an enlarged fragmentary sectional detail view of the lower seal.

Referring more particularly to the drawing, the numeral 10 indicates the bottom of a tank which is adapted to supply the liquid for the vessels to be filled, and the numeral 11 indicates the improved vessel filling valve. The improved valve 11 comprises an elongated tubular member 12 which may be of any suitable length and which may be formed at its upper end with an enlarged portion 13 having an upper externally threaded portion 14 and a lower externally threaded portion 15. The tank 10 is preferably formed with an aperture 16 in the bottom thereof, through which the portion 13 extends and around the margin of which said bottom is formed with a downwardly sloping annular portion 17. The portion 13 is formed at its upper end with an angularly outwardly and upwardly projecting flange 18, the underside of which rests on the upper surface of the annular sloping portion 17. The member 12 may have a portion of increased internal diameter 19 at its upper end. An annular collar 20 is preferably threaded on the threaded portion 14 of the member 12, and an annular gasket 21, of rubber or other suitable material, surrounds the portion 14 between the collar 20 and the under side of the sloping portion 17 of the tank 10. The collar 20 is sufficiently tightened on the portion 14 to prevent leakage past the gasket 21.

A substantially cylindrical stem 22 having an outside diameter equal to the inside diameter of the tube 12 has one end thereof inserted into the lower end of the tube 12 and fixed thereto. The lower end portion of the tube 12 and the upper end portion of the stem 22 are formed with an elongated slot 23 which extends diametrically therethrough as shown in Figs. 2, 3 and 4. At its lower end the stem 22 is formed with a circumferential groove 24 in which is seated an annular sealing ring 25.

Axially slidable on the tube 12 is an upper sleeve 26, and slidable on the lower end of the upper sleeve 26 is a lower sleeve 27. Adjacent its upper end the sleeve 26 has a portion 28 with a bore diameter substantially equal to the outer diameter of the tube 12. At the upper end of the portion 28 the sleeve 26 is formed with an internal annular groove 29 in which is seated an annular sealing ring 30.

Below the portion 28 the sleeve 26 is formed with a portion 31 which has a bore diameter

substantially larger than the bore of the portion 28. Below the portion 31 the sleeve 26 is formed with a portion 32 having a bore diameter substantially equal to the diameter of the stem 22 and having an outside diameter approximately the same as that of the tube 12. The lower end of the portion 32 communicates with a portion 33 having an increased wall thickness which forms a shoulder 34 at the upper end thereof. The portion 33 is formed with an external circumferential groove 35 in which is seated an annular sealing ring 36.

The lower sleeve 27 has a portion 37 which has an axial bore of substantially the same diameter as the outer diameter of the portion 31 of the sleeve 26. Below the portion 37 the sleeve 27 is formed with a chamber 38 of enlarged diameter. A conduit 39 preferably projects through the wall of the sleeve 27 and communicates with the interior of the chamber 38. A flexible tube 40 is connected to the outer end of the tube 39 and communicates by suitable connections (not shown) with any suitable receptacle or with the tank 10 at a point above the level of the fluid therein.

Below the chamber 38, the sleeve 27 is formed with a portion 41 having a bore diameter substantially equal to the outer diameter of the portion 33 of the upper sleeve 26. The lower end of the portion 41 terminates in a flared seat 42. Projecting outwardly and downwardly from the sleeve 27 adjacent the lower end of the chamber 38 is a cup-shaped flange 43 which has an annular internal flare 44 at its lower end. The flange 43 has an inner diameter substantially larger than the outer diameter of the mouth of the vessel 45 to be filled. An annular sealing ring 46, having a substantially triangular cross-sectional shape, is seated in the annular recess 47 formed by the cup-shaped flange 43 in the manner shown in Figs. 2, 3 and 5. The sleeve 27 at its upper end is formed with an internal annular groove 72 in which is seated an annular sealing ring 73.

The sleeve 26 at its upper end is formed with an enlarged portion 48 and is provided with an annular shoulder 49. The sleeves 27 are formed with an external annular shoulder 50, and a helical compression spring 51 is positioned around the sleeves 26 and 27 with its ends abutting the shoulders 49 and 50 of said sleeves, as shown in Figs. 1, 2 and 3.

Threaded onto the portion 15 of the tube 12 is a nut or collar 52 (see Fig. 1). Fixed as by welding to the lower end of the collar 52 is a yoke 53 having a pair of arms 54 and 55 extending outwardly and downwardly from the collar 52 on diametrically opposite sides thereof. A pair of links 56 and 57 are formed with their central portions offset outwardly, and are pivotally connected in these offset portions with the lower ends of the arms 54 and 55 respectively, as at 70 and 71.

Pivoted onto the portion 48 on the sleeve 26, as at 60 and 61, are links 58 and 59. The lower ends of the links 58 and 59 are pivotally connected to end portions of the links 56 and 57, as at 62 and 63. Pivoted onto the portion 31 of the sleeve 27, as at 64 and 65, are a pair of links 66 and 67. The upper ends of the links 66 and 67 are pivotally connected to the ends of the lever 56 and

57 opposite the connections 62 and 63, as at 68 and 69.

In operation, the improved valve, when in shut-off position, is disposed as shown in Figs. 1 and 2. When the parts of the improved valve are so arranged, the stem 22 has its sealing ring 25 positioned in the bore of the portion 32 of the sleeve 26. This seals off the tube 12 and prevents any liquid from passing down from said tube and out through the lower end of the sleeve 26. At the same time, the compression spring 51, by pressing axially against the shoulders 49 and 50, forces the sealing ring 36, which is on the lower end of the sleeve 26, against the bevelled surface 42 on the lower end of the sleeve 27 (see Fig. 5), thereby sealing off the lower end of the sleeve 27. The annular sealing ring 36 is of such size that it will not compress sufficiently to pass into the bore of the portion 41 of the sleeve 27.

When it is desired to fill a vessel, such as the bottle 45 with fluid from the tank 10, the bottle is placed below the lower end of the sleeve 26 in coaxial relationship therewith. Where the improved valve is embodied in a pedestal type vessel filling machine, the bottle 45 is positioned as above stated, on the pedestal below said valve. The pedestal is then actuated in a manner to move the bottle upwardly to a position where the mouth of said bottle abuts the annular sealing ring 46 within the flange 43. Further upward movement of the bottle 45 forces the sleeve 27 upwardly. Through the linkage connecting the sleeves 26 and 27 the sleeve 26 is moved downwardly to the position shown in Fig. 3. This places the lower end portion 33 and a part of the portion 32 of the sleeve 26 within the neck of the bottle 45. It will be noted that the neck of the bottle 45 is of substantially larger internal diameter than the outer diameter of the portion 33 of the sleeve 26 therein. As the sleeve 26 moves downwardly and as the sleeve 27 moves upwardly, the spring 51 is compressed therebetween. Downward movement of the sleeve 26 also moves the portion 32 of said sleeve downwardly away from the lower end of the stem 22 and out of sealing engagement therewith. Upward movement of the sleeve 27 relative to the sleeve 26 moves the flared seat 42 out of sealing engagement with the annular sealing ring 36, as shown in Fig. 3. Since the stem 22 is withdrawn from the portion 32 of the sleeve 26, fluid will now flow down through the tube 12, slot 23, bores of the portions 31 and 32 of the sleeve 26, and into the bottle 45. As a result, fluid will be directed toward the bottom of the bottle 45 in a solid fast moving stream. As fluid thus enters the bottle 45, the air in the bottle, as well as any foam created by the fluid, will pass upwardly around the portion 33 of the sleeve 26, through the bore of the portion 41 at the lower end of the sleeve 27, through the chamber 38 and tube 39, and out through the tube 40 to a suitable receptacle or back into the tank 10, or into a vacuum device.

After the bottle 45 has been filled with liquid, the pedestal and the bottle 45 may then be lowered. Urged by the spring 51, the sleeve 27 will then move downwardly with the bottle 45, and simultaneously the sleeve 26 will move upwardly to the position of Fig. 2. This causes withdrawal of the lower end of the sleeve 26 from the bottle and movement of the portion 32 of said sleeve 26 upwardly around and into sealing engagement with the lower end of the

stem 22. Continued upward movement of the sleeve 26 and downward movement of the sleeve 27 brings the annular sealing ring 36 into sealing engagement with the annular flared seat 42. Upon engagement of the ring 36 with the seat 42, further downward movement of the bottle 45 moves the mouth of said bottle out of engagement with the annular sealing ring 46, and the bottle may then be removed from its position below the filling valve. As the portion 32 of the sleeve 26 moves upwardly into sealing engagement with the lower end of the stem 22, the flow of fluid downwardly through the tube 12 is shut off, and as the sealing ring 36 engages the flared annular seat 42, the portion 41 of the lower sleeve 27 is sealed off, thereby preventing any foam or fluid from flowing back into the bottle from the chamber 38.

It will be noted that the improved valve delivers a large volume of liquid in a centrally located stream to the bottom of the vessel being filled, and that the liquid then rises in the bottle around the entering stream, driving the air and the foam out of the top so that it may be carried away to the tube 40. Due to the fact that the entering liquid is in the form of a solid stream flowing at high velocity, the tendency of the fluid to foam is reduced and large bubbles are produced which are easily eliminated.

The improved valve is particularly well adapted for use in a pedestal type vessel filling machine since it can be operated by merely raising a bottle into operative relationship therewith and no other operating mechanism is necessary. By reason of its novel construction, the improved valve is fast and positive in operation.

The linkage connecting the sleeves 26 and 27 materially reduces the length of time necessary to open and close the improved valve inasmuch as both of said sleeves are moved simultaneously in opposite directions rather than successively in the same direction.

The improved valve is easily disassembled and cleaned and is well adapted for use in food industries.

Various changes and modifications may be made without departing from the spirit of the invention, and all of such changes are contemplated, as may come within the scope of the claims.

What I claim is:

1. A vessel filling valve comprising a liquid inlet conduit; a first sleeve telescopically associated with said conduit, said sleeve having an end portion adapted to be positioned in a vessel to be filled; a second sleeve telescopically associated with said first sleeve, said second sleeve having a vessel-mouth-sealing portion and also having a vent; linkage connecting said first and second sleeves and responsive to telescopic movement of said second sleeve for causing telescopic movement of said first sleeve; and means responsive to said telescopic movement of said first sleeve in one direction for preventing the flow of fluid through said first sleeve.

2. A vessel filling valve comprising a liquid inlet conduit; a first sleeve telescopically associated with said conduit, said sleeve having an end portion adapted to be positioned in a vessel to be filled; a second sleeve telescopically associated with said first sleeve, said second sleeve having a vessel-mouth-sealing portion and also having a vent; linkage connecting said first and second sleeves and responsive to telescopic movement of said second sleeve for causing telescopic move-

ment of said first sleeve in the opposite direction; and means responsive to said telescopic movement of said first sleeve in one direction for preventing the flow of fluid through said first sleeve.

3. A vessel filling valve comprising a liquid inlet conduit; a stem carried by said inlet conduit; a first sleeve telescopically associated with said conduit and with said stem, said sleeve having an end portion adapted to be positioned in a vessel to be filled; a second sleeve telescopically associated with said first mentioned sleeve, said second sleeve having a vessel-mouth-sealing portion and also having a vent; and linkage connecting said first and second sleeves, said stem being positioned to prevent the flow of fluid through the first sleeve after said first sleeve has been telescopically moved in one direction by said linkage in response to telescopic movement of said second sleeve.

4. A vessel filling valve comprising a liquid inlet conduit; a first sleeve telescopically associated with said conduit, said sleeve having an end portion adapted to be positioned in a vessel to be filled; a second sleeve telescopically associated with said first sleeve, said second sleeve having a vessel-mouth-sealing portion and also having a vent; linkage connecting said first and second sleeves and responsive to telescopic movement of said second sleeve for causing telescopic movement of said first sleeve; means responsive to said telescopic movement of said first sleeve in one direction for preventing the flow of fluid through said first sleeve; and means on said first sleeve responsive to telescopic movement thereof in said direction for sealing the vent in said second sleeve.

5. A vessel filling valve comprising a liquid inlet conduit; a first sleeve telescopically associated with said conduit, said sleeve having an end portion adapted to be positioned in a vessel to be filled; a second sleeve telescopically associated with said first sleeve, said second sleeve having a vessel-mouth-sealing portion and also having a vent; linkage connecting said first and second sleeves and responsive to telescopic movement of said second sleeve for causing telescopic movement of said first sleeve; and means responsive to said telescopic movement of said first sleeve in one direction for preventing the flow of fluid through said first sleeve and for sealing said vent.

6. A vessel filling valve comprising a vertically extending liquid inlet conduit; a first sleeve telescopically associated with said conduit and having an end portion adapted to be positioned in the vessel to be filled; a stem carried by said conduit and normally positioned to prevent the flow of fluid through said first sleeve; a second sleeve telescopically associated with said first sleeve, said second sleeve having a vessel-mouth-sealing portion and also having a vent; and linkage connecting said first and second sleeves for simultaneous movement in opposite directions, whereby a predetermined upward movement of said second sleeve causes simultaneous downward movement of the first sleeve to a position wherein fluid is permitted to flow therethrough.

7. A vessel filling valve comprising a vertically extending liquid inlet conduit; a first sleeve telescopically slidably on said conduit and having an end portion adapted to be positioned in a vessel to be filled; a stem carried by said conduit and normally positioned to prevent the flow of fluid through the first sleeve; a second sleeve telescopically slidably on said first sleeve, said sec-

ond sleeve having a vessel-mouth-sealing portion and also having a vent, there being an annular space between said sleeves adjacent said mouth sealing means, said annular space communicating with said vent and with the vessel engaging side of said mouth-sealing means; means on said first sleeve normally sealing off the annular space between said first and second sleeves; and linkage connecting said first and second sleeves for simultaneous movement in opposite directions, whereby a predetermined upward movement of said second sleeve causes simultaneous downward movement of said first sleeve to a position wherein fluid is permitted to flow therethrough and wherein the annular space between said sleeves is open.

8. A vessel filling valve comprising a liquid inlet conduit; a first sleeve telescopically associated with said conduit, said sleeve having an end portion adapted to be positioned in a vessel to be filled; a second sleeve telescopically associated with said first sleeve, said second sleeve having a vessel-mouth-sealing portion and also having a vent; linkage connecting said first and second sleeves and responsive to telescopic movement of said second sleeve for causing telescopic movement of said first sleeve, said linkage including a lever fulcrumed intermediate its length, a first link pivotally connected at one end to said first sleeve and at the other end to one end of said lever, and a second link pivotally connected at one end to said second sleeve and at the other end to the other end of said lever; and means responsive to said telescopic movement of said first sleeve in one direction for preventing the flow of fluid through said first sleeve.

9. A vessel filling valve comprising a liquid inlet conduit; a first sleeve telescopically associated with said conduit, said sleeve having an end portion adapted to be positioned in a vessel to be filled; a second sleeve telescopically associated with said first sleeve, said second sleeve having a vessel-mouth-sealing portion and also having a vent; a pair of levers pivotally supported intermediate their length on opposite sides of said conduit; a first pair of links each pivotally connected at one end to one end of said levers and at the other end to said first sleeve; a second pair of links each pivotally connected at one end to the other end of one of said levers and at the opposite end to said second sleeve, said levers and links being arranged to cause telescopic movement of said first sleeve in response to telescopic movement of said second sleeve; and means responsive to said telescopic movement of said first sleeve in one direction for preventing the flow of fluid through said first sleeve.

10. A vessel filling valve comprising a liquid inlet conduit; a first sleeve member telescopically associated with said conduit, said sleeve having an end portion adapted to be positioned in a vessel to be filled; a second sleeve telescopically associated with said first sleeve, said second

5 sleeve having a vessel-mouth-sealing portion and also having a vent; a yoke fixed to said inlet conduit and having a pair of depending arms positioned on opposite sides of said conduit; a lever pivotally connected intermediate its length to each of said arms; a first pair of links each pivotally connected at one end to one end of one of said levers and at the other end to said first sleeve; a second pair of links each pivotally connected at one end to the other end of one of said levers and at the opposite end to said second sleeve, said levers and links being arranged to cause telescopic movement of said first sleeve in response to telescopic movement of said second sleeve; and means responsive to said telescopic movement of said first sleeve in one direction for preventing the flow of fluid through said first sleeve.

11. A vessel filling valve comprising a liquid inlet conduit; a first sleeve member telescopically associated with said conduit, said sleeve having an end portion adapted to be positioned in a vessel to be filled; a second sleeve telescopically associated with said first sleeve, said second sleeve having a vessel-mouth-sealing portion and also having a vent; a yoke fixed to said inlet conduit and having a pair of depending arms positioned on opposite sides of said conduit; a lever pivotally connected intermediate its length to the lower end of each of said arms; a first pair of links each pivotally connected at one end to one end of said levers and at the other end to said first sleeve; a second pair of links each pivotally connected at one end to the other end of one of said levers and at the opposite end to said second sleeve, said levers and links being arranged to cause telescopic movement of said first sleeve in response to simultaneous telescopic movement of said second sleeve in the opposite direction; and means responsive to said telescopic movement of said first sleeve in one direction for preventing the flow of fluid through said first sleeve.

12. A vessel filling valve comprising a vertically extending liquid inlet conduit; a first sleeve telescopically associated with said conduit and having an end portion adapted to be positioned in a vessel to be filled; a stem carried by said conduit and normally positioned to prevent the flow of fluid through said first sleeve; a second sleeve telescopically associated with said first sleeve, said second sleeve having a vessel-mouth-sealing portion and also having a vent; linkage connecting said first and second sleeves for simultaneous movement in opposite directions, whereby a predetermined upward movement of said second sleeve causes simultaneous downward movement of the first sleeve to a position wherein fluid is permitted to flow therethrough, and means for urging said first and second sleeves in opposite axial directions.
